(57) **CLAIM**

The ornamental design for a foot cuff with a tapered, blunt end, as shown and described.

DESCRIPTION

FIG. 1 is a top plan view of a first embodiment of a foot cuff with a tapered, blunt end showing our new design;

FIG. 2 is a bottom plan view of the foot cuff;

FIG. 3 is a front elevational view of the foot cuff;

FIG. 4 is a rear elevational view of the foot cuff;

FIG. 5 is a left side elevational view of the foot cuff;

FIG. 6 is a right side elevational view of the foot cuff;

FIG. 7 is a top plan view of a second embodiment of a foot cuff with a tapered, blunt end showing our new design; and,

FIG. 8 is a bottom plan view of the foot cuff shown in FIG. 7. The phantom lines in the drawings indicate environmental structure which forms no part of the claimed design.

The broken lines in the FIGS. 7 and 8 indicate portions of the foot cuff which form no part of the claimed design.
